SPEEDOMETER CABLE FITTING LOCK

George S. Kontra, Oshkosh, Wis.

Application February 21, 1949, Serial No. 77,470

3 Claims. (Cl. 70—232)

1

This invention relates to improvements in speedometer cable fitting locks.

There are many instances when it is desired or necessary to accurately check on the mileage travelled by a particular automobile. This can ordinarily be done only by means of the mileage indicated on the speedometer of the automobile. Concerns which make a business of renting "Drive Yourself" automobiles have particular difficulty in keeping an accurate check on the mileage travelled by their rented vehicles because unscrupulous persons may disconnect the speedometer cable from the speedometer to prevent the recording by the speedometer of a certain part of the distance travelled.

To prevent this practice, locks have heretofore been devised. These locks, while being effective to prevent undetected disconnection of speedometer cables, are of a design which requires a rather complicated installation operation and, in addition, has to be sawed off and thereby partially destroyed in order to be removed. There are times, such as for resetting of the speedometer or for repair thereof, when owners of rental cars wish to have access to the speedometer cable connector nuts of their cars, and it is desirable that such access be quick and easy and without the expense of replacement of parts.

It is therefore a general object of the invention to provide a key operated lock which prevents disconnection of a speedometer cable by preventing access to the connector nut thereof.

A further object of the invention is to provide a device of the class described which may be readily installed or removed by means of a key, but which cannot be otherwise removed without destruction thereof.

Another object of the invention is to provide a device of the class described having a housing which completely encloses the speedometer cable attaching nut and which is separable into two parts, said housing parts being hingedly inter-fitted at one end and being locked in abutment at their other ends by a tumbler equipped screw plug which is turnable only upon insertion therein of the proper key.

A further object of the invention is to provide a device of the class described which is strong and durable, which is simple in construction, which is easy to manufacture, and which is otherwise well adapted for the purposes described.

With the above and other objects in view, the invention consists of the improved speed-

2

ometer cable fitting lock, and all of its parts and combinations, as set forth in the claims, and all equivalents thereof.

In the drawings accompanying and forming a part of this specification, wherein is shown one complete embodiment of the preferred form of the invention, and wherein the same reference characters indicate the same parts in all of the views:

10. Fig. 1 is a side view of the improved lock in operative position around a speedometer cable connector nut;

Fig. 2 is a vertical sectional view taken along the line 2—2 of Fig. 1;

15. Fig. 3 is a vertical sectional view taken along the line 3—3 of Fig. 1;

Fig. 4 is a side view of the removable, tumbler-equipped, screw plug of the invention, with the tumblers thereof retracted by the insertion of 20 a key; and

Fig. 5 is a vertical sectional view taken along the line 5—5 of Fig. 3.

Referring more particularly to the drawing, the numeral 35 indicates a conventional speedometer having a connector nipple 32 through which one end of a speedometer cable 36 removably extends and to which a speedometer cable connector nut 31 is threadably connected. The nut 31 is mounted on one end of a speedometer cable housing 33 through which the cable 36 rotatably extends.

The numeral 10 indicates a housing which is split into two complementary body members as indicated by the numerals 11 and 12. The housing 10 is formed with a cylindrical chamber 13, communicating with one end of which is an aperture 14 which aperture extends through the sidewall of the housing 10. A second aperture 15 is coaxial with the aperture 14 and the chamber 13, and said aperture extends through the sidewall of the housing 10 opposite the aperture 14.

The body member 11 of the housing 10 is formed with an upstanding flange 16 having an aperture 17 therethrough, and the body member 12 of the housing 10 is formed with an upwardly curved tongue 18 which removably projects through the aperture 17, as is clearly shown in Figs. 1 and 3. The body member 11 of the housing 10 is formed with a bore 19 and with a coaxial threaded bore 20 both of which extend at substantially a right angle to the axis of the cylindrical chamber 13. The body member 12 of the housing 10 is formed with a bore 21 which is coaxial with the bores 19 and 20. The bore 21

is preferably formed with four equally spaced, axially extending grooves 22, and is formed with a portion of enlarged diameter 23 at the outer end of the bore 21 to provide a shoulder 23'.

Referring to Figs. 3 and 4, a screw plug 24 is formed at one end with exterior threads 25 and at the other end with an enlarged head or shoulder 26. The plug 24 is formed with a cut out portion 27 in which are mounted a plurality of spring loaded tumblers 28. The tumblers 28 normally assume the position shown in Fig. 3. An axially extending key slot 29 (see Fig. 1) communicates with the cut out portion 27 in the plug 24, and when a key 30 is inserted in the slot 29, the tumblers 28 are retracted to the position of Fig. 4. The construction and operation of the tumblers 28 is not new, so details thereof will not be given here.

To install the improved lock, it is only necessary to take the complementary body members 11 and 12 of the housing 10, with the screw plug 24 removed therefrom, and place said members around the speedometer cable connector nut 31 with the tongue 18 extending through the slot 17. Since the speedometer cable connecting nut 31 is threaded onto the speedometer connector nipple 32, the latter projects through the aperture 15 and the speedometer cable housing 33 projects through the aperture 14, as is clearly shown in Fig. 5.

With the complementary body members of the housing 10 in the position of Figs. 2 and 3, the screw plug 24, with the key 30 therein (as shown in Fig. 4) to retract the tumblers 28, is inserted in the bore portions 19, 21 and 23. By turning the key 30 the portion 25 of the plug 24 may be threaded into the threaded bore 20. This is continued until the enlarged head 26 is seated in the bore portion 23 against the shoulder 23'. At this point the tumblers 28 are in alignment with the grooves 22 and, therefore, removal of the key 30 allows the tumblers 28 to spring outwardly into the grooves 22 to the positions shown in Fig. 3. Projection of the tumblers 28 into the grooves 22 prevents rotation of the plug 24. The body member 12 of the housing 10 cannot move away from the body member 11 because of the engagement of the enlarged head 26 of the plug 24 with the shoulder 23'. The chamber 13 and the apertures 14 and 15 are preferably sufficiently large so as not to bind the cable housing 33, connector nut 31 or nipple 32, but nevertheless fit snugly enough to completely enclose the connector nut 31 and prevent access thereto when the lock is installed.

The improved lock can be quickly removed by insertion of the key 30 in the slot 29, and by then unscrewing the plug 24 by the use of said key to thereby remove said plug from the housing 10. Removal of the plug 24 from both portions of the housing 10 permits said portions to be hingedly swung apart and to be lifted off of the connector nut 31, thereby providing access to said nut.

The improved lock prevents tampering with the operation of the speedometer and can be readily transferred from one automobile to another without the necessity of replacing any parts thereof.

While the improved lock is shown and its use is described in association with the upper end of the speedometer cable, it is obvious that it may be similarly used on the fitting nut which connects the lower end of the cable to the transmission. It is also obvious that the invention

may readily be adapted for use as a protective device in many other applications, such as on union nuts of gas meters or the like.

Various changes and modifications may be made without departing from the spirit of the invention, and all of such changes are contemplated as may come within the scope of the claims.

What I claim is:

1. A fitting lock comprising a housing formed of a pair of normally abutting complementary body members having cooperating hollowed portions forming a chamber for enclosing a connector nut, said chamber having oppositely disposed end openings, the first of said body members being formed in an abutting surface at one side of said chamber with a threaded recess having a closed inner end and said body member being formed with an outwardly projecting apertured flange on the opposite side of said chamber, and the second of said body members being formed with a bore therethrough coaxial with said threaded bore and being formed with an outwardly projecting curved tongue which is insertable through the aperture in the flange of the first body member to form a hinged connection between said members; and a tumbler equipped key operated screw plug having a portion removably insertable through the bore of said second member and engageable with the threaded bore of said first member to maintain the two housing members in abutment while said members are in enclosing relationship with a connector nut, there being means on the wall of one of said bores positioned to coat with the tumblers of the screw plug to lock said plug against rotation when it is positioned in both of said bores.

2. A fitting lock comprising a housing formed of a pair of normally abutting complementary body members having cooperating hollowed portions forming a chamber for enclosing a speedometer cable connector nut, said chamber having oppositely disposed end openings, the first of said body members being formed in an abutting surface at one side of said chamber with a threaded recess having a closed inner end and said body member being formed with a hinge member on the opposite side of said chamber, and the second of said body members being formed with a bore therethrough coaxial with said threaded bore and being formed with a hinge member engageable with the hinge member of the first body member; and a tumbler equipped key operated screw plug having a portion removably insertable through the bore of said second member and engageable with the threaded bore of said first member, said screw plug also having shoulder means engageable with said second body member when said plug is so inserted and engaged to maintain the two housing members in abutment while said members are in enclosing relationship with a connector nut, there being means on the wall of one of said bores positioned to coat with the tumblers of the screw plug to lock said plug against rotation when it is positioned in both of said bores.

3. A fitting lock comprising a housing formed of a pair of normally abutting complementary body members having cooperating hollowed portions forming a chamber for enclosing a speedometer cable connector nut, said chamber having oppositely disposed end openings, the first of said body members being formed in an abutting surface at one side of said chamber with a

threaded recess having a closed inner end and said body member being formed with an outwardly projecting apertured flange on the opposite side of said chamber, and the second of said body members being formed with a bore therethrough coaxial with said threaded bore and being formed with an outwardly projecting curved tongue which is insertable through the aperture in the flange of the first body member to form a hinged connection between said members; and a tumbler equipped key operated screw plug having a portion removably insertable through the bore of said second member and engageable with the threaded bore of said first member, said screw plug also having shoulder means engageable with said second body member when said plug is so inserted and engaged, to maintain the two housing members in abutment while said

members are in enclosing relationship with a connector nut, there being means on the wall of one of said bores positioned to coact with the tumblers of the screw plug to lock said plug against rotation when it is positioned in both of said bores.
